UNITED STATES PATENT OFFICE

JOHN C. LEUKHARDT, JR., OF WASHINGTON, DISTRICT OF COLUMBIA

CIGARETTE AND MATCH PACK

Application filed February 23, 1932. Serial No. 594,702.

This invention relates to cigarette packages and particularly to an improved type of package which comprises a wrapper and jacket enclosing a plurality of cigarettes and a pack or supply of matches, the whole arranged as a unitary article of manufacture.

The main objects of this invention are to provide an improved single marketing package for cigarettes which includes a pack of 10 individually accessible matches; to provide such a package in which the cigarettes and match pack are held by a common wrapper but in separate compartments; to provide a cigarette package having a match pack 15 secured thereto by a single common wrapper arranged so that the cigarettes and matches respectively are individually accessible; to provide such a package containing a plurality of self-lighting matches having outwardly disposed means to effect their individual removal and utilization; and to provide a 20 single package comprising a sealed compartment for cigarettes and a separate compartment for a match pack, the whole enclosed 25 in a common wrapper arranged to provide separate access to the matches and the cigarettes respectively.

A specific embodiment of this invention is shown in the accompanying drawings, in 30 which:

Figure 1 is a view showing a cigarette and match package as held in the hands when beginning the operation of removing a match.

Fig. 2 is a view of the same showing the position of the package and hands when removing a match.

Fig. 3 is a partial view of the package partly broken away to show a longitudinal 40 section of the match pack.

Fig. 4 is a view taken on line 4—4 of Fig. 3 showing the match pack in plan.

Fig. 5 is a view taken on line 5—5 of Fig. 3 showing a transverse section of the 45 match pack.

Fig. 6 is a partial side view of a package showing the end arrangement of the match pack and the disposition of the match pulls.

Fig. 7 is a perspective view showing the 50 method of wrapping a package to incorporate a match pack, the outer wrapper being broken away to show the folds of the inner wrapper.

Fig. 8 is a partially sectioned view of the 55 same showing the first folding operation of the end of the outer wrapper.

Fig. 9 is an enlarged perspective view of the same showing the end of the outer wrapper folded to receive the match pack which is shown in dotted outline. 60

Fig. 10 is a view of the same showing the match pack in place and the folded wrapper ends secured to hold the match pack.

In the form shown in the drawings, the 65 improved cigarette and match pack 1 comprises an inner wrapper 2 formed to enclose a plurality of cigarettes 3, an outer wrapper or jacket 4 which surrounds the package and finishes the same for marketing, and a match pack 5 secured at the bottom of the 70 package 1 against the folded ends of the inner wrapper 2 and held as an integral part of the package by means of the jacket 4, the ends of which are formed as flaps and folded over the match pack 5 to secure the 75 same against displacement.

In the form shown, the match pack 5 comprises a bottom portion 6 formed to provide a plurality of individual compartments or channels for matches, the compartments being defined by longitudinal partitions 7 extending endwardly from a central transverse dividing member 7.1. The upper portion 8 forms the cover for the match pack, and completes the housing for the matches 9, which are placed, one in each of the several compartments or channels and arranged so that the match head 10 is disposed toward the center of the pack. 80

The matches 9 extend endwardly from the 85 center of the match pack, being of suitable length so their ends will be flush with the ends of the pack, and each of the matches 9 is provided with a string or pull 11 which extends beyond the ends of the matches and is folded upon and detachably secured to the sides of the package, as shown in Fig. 3. The withdrawing means or pulls 11 on the matches are secured to the package by means of a strip 12 of glue or other suitable material, and are so arranged that they may be individually detachable from the package to permit the extraction of the matches, one at a time. 95

As shown in Figures 3 and 4, the upper 100 and lower sides of the end portion of each match compartment is provided with an abrasive surface 13, which is so disposed that the thickness of the compartment in which each match is placed will be restricted at the outer ends, to grip the head 10 of a match as it is being withdrawn, in order to automati- 105 110

cally cause the match to ignite. The thickness of the match compartments is preferably reduced gradually as it approaches the outer end of the pack so that a match, on being withdrawn, will be somewhat retarded and cause the user to exert a sudden pull or jerk to remove the match. In this way a rapid and certain ignition of the match will be attained.

- 10 As shown in Figures 7 to 10, inclusive, the cigarette and match package is formed by first enclosing the cigarettes in the inner wrapper 2, the ends of which are folded over to present a secure and substantially airtight inner package. The outer wrapper or jacket 4 is then placed about the package so as to extend somewhat beyond one of its ends and the side portions 14 of the jacket extension are folded inwardly against that end, as 15 shown in Figures 8 and 9, so that the front and back portions of the jacket will remain as a pair of flaps 15. The match pack 5, which is formed to have a face area substantially equivalent to the area of the end of 20 the package, is then placed between the flaps 15 and against the end of the package, as shown in Figures 9 and 10, and the flaps 15, which embrace the match pack, are folded to overlap each other and are secured to hold 25 the match pack in position as an integral part of the complete package 1. The strings or pulls 11 are then secured to the sides of the package in a manner permitting individual and selective removal and the completed 30 package is ready for marketing.

In operation, the package 1 is preferably held, as shown in Fig. 1, and after a cigarette 3 has been extracted from the package, one of the strings or pulls 11 is detached 40 from the side of a package by means of the user's fingernail, and a match 9 is partially extracted from its respective compartment. As shown in Figure 2, the hand is then turned and the match is gripped between 45 the thumb and forefinger and quickly pulled or jerked from the match pack.

The sudden pulling of the match causes the friction surface 13 to ignite the head 10 of the match, which flares the instant the 50 match has been withdrawn from its compartment. The hand used to withdraw the match will then be in a naturally cupped position so as to shield the flame from any breeze or air currents that might tend to 55 extinguish it, and the cigarette, held in the user's mouth, is easily and quickly lighted.

With the arrangement of matches in the form shown, the danger of burning the user's fingers through the necessity of turning the match in order to hold it so that it will be shielded in the cupped hand, is 60 completely obviated, since in the natural manner in which the matches are extracted, the hand is initially in a cupped position, 65 and the match is properly held so that the

cigarette can be readily lighted with very little likelihood of the match being blown out by any air currents that might be present.

In the form shown, the match pack 5 is 70 constructed so that each match 9 is completely housed in its own respective compartment or channel, and there is no likelihood of the remaining matches being inadvertently ignited when one of the matches is being 75 withdrawn, or pulled between the friction surfaces 13. Also, the upper and lower portions 6 and 8 are preferably made from a suitable heavy material so that there will be 80 no danger of the heat of ignition setting fire to any part of the package.

The particular advantages of my improved cigarette and match pack lie in the fact that a single compact package is provided to hold an adequate supply of automatically ignited matches, and the nuisance of having to search for a match or a light when it is desired to smoke is completely 85 obviated.

It is a well known fact that smokers are 90 continually bothered by the lack of matches or other cigarette-lighting means, and providing a suitable and adequate supply of matches, which are individually accessible, in the same packages as the cigarettes, not 95 only conserves the smoker's time and patience, but further provides in a unitary article the necessary smoking devices that would otherwise be contained in separate packages which must of necessity require 100 more space and might be kept in separate places.

Compact carrying cases, designed to hold a package of cigarettes and a package of matches, have long been in use. However, 105 the necessity of obtaining a supply of matches at the same time a package of cigarettes is purchased, has not been eliminated, and the advantage of my improved cigarette and match pack in this regard, lies 110 in the fact that an adequate supply of matches is always present with a supply of cigarettes, the matches and cigarettes being combined in a single package by the cigarette manufacturer. Furthermore, the 115 nuisance to the cigarette retailer of having to provide and handle separate packages of matches is eliminated.

Although but one specific embodiment of this invention has been herein shown and described, it will be understood that certain details of the construction shown may be altered or omitted without departing from the spirit of this invention as defined by the following claims.

I claim:

1. As an article of manufacture, a cigarette package having a pair of flaps, in combination with a match pack secured by said flaps, said match pack comprising a 130

- plurality of matches having individual withdrawing means projecting from their ends, said withdrawing means being detachably secured to a wall of said cigarette package.
5. 2. As an article of manufacture, a cigarette package comprising a wrapper enclosing a plurality of cigarettes grouped to form a rectangular package, an outer jacket surrounding said package and having oppositely disposed flaps extending beyond an end of said package, and a match pack comprising a plurality of individually removable matches disposed between said flaps and embraced thereby.
10. 3. As an article of manufacture, a cigarette package comprising a wrapper enclosing a plurality of cigarettes grouped to form a rectangular package, a jacket surrounding said package and extending beyond an end thereof, opposite sides of said jacket extension folded inwardly against the end of said package, endwardly projecting flaps formed by the remaining portions of said extension, and a match pack disposed between said flaps and against the inwardly folded sides of said jacket extension, said flaps embracing and securing said match pack.
15. 4. As an article of manufacture, a cigarette package comprising a wrapper enclosing a plurality of cigarettes grouped to form a rectangular package, a jacket surrounding said package and extending beyond an end thereof, opposite sides of said jacket extension folded inwardly against the end of said package, endwardly projecting flaps formed by the remaining portions of said extension, a match pack comprising a plurality of slidably removable matches disposed between said flaps and against the inwardly folded sides of said jacket extension, and means extending from each of said matches to effect individual removal of the same, said jacket flaps embracing and securing said match pack.
20. 5. As an article of manufacture, a cigarette package comprising a wrapper enclosing a plurality of cigarettes grouped to form a rectangular package, an outer jacket surrounding said package and having its ends folded to enclose the same, a match pack positioned against a folded end of said inner wrapper and comprising a plurality of individually removable matches, an outer wrapper formed to embrace the wrapped cigarettes and said match pack collectively, said outer wrapper being arranged to provide an opening positioned to expose the ends of said match pack, individual withdrawing means projecting from the end of each of said matches, and means collectively securing said withdrawing means to said cigarette package.
25. 6. As an article of manufacture, a cigarette package comprising a wrapper enclosing a plurality of cigarettes grouped to form a rectangular package, a jacket surrounding said package and having oppositely disposed flaps extending beyond an end of said package, a match pack comprising a plurality of individually removable matches disposed between said flaps and embraced thereby, and means extending from each of said matches to effect individual removal of the same, said means being extended along the sides of the package and detachably fastened to said jacket.
30. 7. As an article of manufacture, a cigarette package comprising a wrapper girding a rectangular group of parallel cigarettes and having side portions extending beyond the ends of said cigarettes, said side portions being folded inwardly over the ends of said cigarettes to enclose said cigarettes and form an inner package, an outer wrapper surrounding the inner package and forming a jacket therefor, oppositely positioned endwardly extending flaps on said outer wrapper, and a match pack positioned between said flaps against the end of said inner package, said flaps being folded inwardly to embrace said match pack and overlapped to secure the same.
35. 8. As an article of manufacture, a cigarette package comprising an inner wrapper surrounding a plurality of cigarettes and having its ends folded to enclose the same, a match pack positioned against a folded end of said inner wrapper and comprising a plurality of individually removable matches, an outer wrapper formed to embrace the wrapped cigarettes and said match pack collectively, said outer wrapper being arranged to provide an opening positioned to expose the ends of said match pack, individual withdrawing means projecting from the end of each of said matches, and means collectively securing said withdrawing means to said cigarette package.
40. 9. In a cigarette package comprising a match pack having a plurality of individually removable matches, withdrawing means projecting from the ends of said matches, and means securing said withdrawing means against a wall of said cigarette package, said withdrawing means being individually detachable from said package wall.
45. 10. In a cigarette package comprising a match pack, positioned against a wall of said package and having a plurality of individually removable matches, means projecting from the ends of said matches for effecting individual removal of the same, said means being flexibly connected to said matches and disposed at an angle relative to said matches and against another wall of said package.
